UNITED STATES PATENT OFFICE.

ELMER I. YOUNG, OF MONTCLAIR, NEW JERSEY, ASSIGNEE, BY DIRECT AND MESNE ASSIGNMENTS, TO Y. & B. MANUFACTURING COMPANY, A CORPORATION OF NEW JERSEY.

RAZOR-STROPPING DEVICE.

952,168.

Specification of Letters Patent. Patented Mar. 15, 1910.

Application filed January 27, 1909. Serial No. 474,405.

To all whom it may concern:

Be it known that I, ELMER I. YOUNG, a citizen of the United States, residing at Montclair, in the county of Essex and State 5 of New Jersey, have invented a new and useful Razor-Stropping Device, of which the following is a specification.

My invention relates to improvements in razor-stropping devices, and more particularly to devices for stropping razor blades 10 used in safety razors.

The objects of my invention are, first, to provide a stropping device simple in its construction, but positive in its action; second, 15 a stropping device in which there is no mechanism intermediate of the friction-roller and the blade-holder; third, to provide a stropping-device adapted to strop blades of any thickness, with or without backs; fourth, to 20 increase the surface of contact between the friction-roller and the strop; and fifth, a stropping device that can be quickly and easily taken apart or assembled.

Further and other objects will more definitely appear from the detailed description 25 to follow.

I accomplish the objects of my invention by the devices and means described in the following specification.

30 The invention is clearly defined and pointed out in the claims.

A structure embodying the features of my invention is illustrated in the accompanying drawings, forming a part of this specification, 35 in which—

Figure 1 is a top view of my improved stropping-device, showing a razor-blade held in one stropping position by the blade-holder. Fig. 2 is a side view. Fig. 3 is an 40 end view, showing a razor strop and blade *in situ*. Fig. 4 is an enlarged perspective view of an auxiliary blade-holder.

In the drawings, similar letters of reference refer to similar parts throughout the 45 several views.

Referring to the drawings, the frame of my improved razor-stropping device consists of a base-plate A and parallel standards D D rigidly secured thereto, said standards 50 D D being connected to each other by the member D¹ and adapted to support a strop S. The base-plate A is preferably formed from sheet metal, suitably shaped by bending the metal over upon itself and bringing 55 the ends together at right angles thereto to

form a lug or clamping-member C to which the handle B is secured. This handle B is preferably formed U-shaped from spring wire, the ends having notches b b which will engage the clamping-member C when the 60 handle B is placed therein. As shown in the drawings, the connecting-member D¹ is preferably made integral with the standards D D.

Removably secured to the base-plate A, 65 and perpendicular thereto, are two parallel spindles E E¹ connected by a connecting piece E''. Upon the spindle E is revolvably mounted the blade-holder F while upon the spindle E¹ is revolvably mounted the friction-roller G, preferably made of rubber, though any other suitable material may be used. Suitable means are provided for actuating the blade-holder by the roller G. In the best embodiment of my invention, I arrange 70 the spindles E E¹ adjacent to each other, so that the roller G will be in frictional contact with the blade-holder and the travel of the blade will be away from and on either side of the roller G. As shown in the 75 drawings, I prefer to form the two spindles E E¹ integral with the connecting piece E'', and removably secured to the base-plate A in a plane perpendicular to the plane of the standards D D. The ends of the spindles 80 E E¹ pass through the base-plate A into the clamping-member C, where they are held rigidly in place by a screw H which passes through C and engages the notches e e in the 85 ends of the spindles E E¹.

The standards D D are secured to the base-plate A at points above the plane of the lower surface of the roller G, so that when the strop S passes over the standards D D and under the roller G, it will tend to envelop the roller G and thus largely increase 90 the surface of contact between the roller G and the strop. As the device is moved over the strop, the base plate A will act as a guide, thus keeping the roller and blade- 95 holder transverse to the strop.

The blade-holder F may be of any desired construction adapted to firmly hold a razor blade K while being stropped. As shown, the blade-holder F is provided with two 100 spring jaws f f which are adapted to receive and hold firmly the back k of the blade K. When it is desired to strop blades having no backs, I provide an auxiliary blade-holder L formed from a strip of 105

metal bent over upon itself and having edges l to engage the blade, and lips l' for the entrance of the blade. This auxiliary blade-holder L is adapted to be inserted in the 5 blade-holder F and to be held firmly by the jaws f .

My improved stropping device is adapted to be used with the ordinary and well-known form of strop, which usually is a strip of 10 leather. As indicated in Fig. 3, the strop S runs over the two standards D and under the roller G . As the stropping-device is moved backward and forward, the friction of the strop upon the roller G causes 15 the latter to rotate upon the spindle E^1 and directly actuate the blade-holder F , which will hold the blade K against the strop at the proper angle for stropping. As soon as the movement of the device over the strop 20 is reversed, the roller G will reverse its rotation and cause the blade-holder F to oscillate or reverse and assume the dotted position shown in Fig. 3. By removing the screw H , the spindle E E^1 can be withdrawn from 25 the base-plate, in order to receive a new blade-holder or a new friction-roller if desired, and the handle B can then be withdrawn. The parts can be re-assembled in the reverse order.

30 While I have shown and described a device embodying my invention in the form preferred by me, yet it is capable of considerable structural variation without, however, departing from the spirit of my invention.

35 What I claim as new, and desire to secure by Letters Patent, is:

1. In a razor-stropping device, the combination of a base plate adapted to guide the strop, a handle secured thereto, for imparting bodily movement to the device, a 40 friction member to engage the strop, and a bladeholder in frictional contact with the peripheral surface of said friction member.

2. In a razor-stropping device, the combination of a frame adapted to support and 45 guide the strop, a handle secured to the frame for imparting bodily movement thereto, a roller to engage the strop, and a bladeholder in frictional contact with the peripheral surface of said roller.

3. In a razor-stropping device, the combination of a base plate formed from sheet metal bent over upon itself to form a lug, a handle secured to said lug, a roller to 55 engage the strop, and a bladeholder in frictional contact with the peripheral surface of said roller.

4. In a razor-stropping device, the combination of a base plate, a handle, means for 60 removably securing said handle to said base plate, a roller to engage the strop, and a bladeholder in frictional contact with the peripheral surface of said roller.

5. In a razor-stropping device, the combination of a base-plate formed from sheet

metal bent over upon itself to form a lug, a handle secured to said lug, and a plurality of standards to support the strop secured to said base-plate.

6. In a stropping device, the combination 70 of a base plate, a handle secured thereto, a roller to engage the strop, a bladeholder in frictional contact with the peripheral surface of said roller, and means for increasing the surface of contact between said roller 75 and the strop.

7. In a razor-stropping device, the combination of a base plate, a handle secured thereto, a blade-holder, a friction-member to engage the strop, and in frictional contact 80 with said blade-holder, and means for increasing the surface of contact between said friction-member and the strop.

8. In a razor-stropping device, the combination of a frame, a handle secured thereto, 85 a plurality of parallel spindles secured to said frame, means for removably securing said spindles to said frame, a blade-holder revolvably mounted on one of said spindles, and a friction-member mounted on another 90 of said spindles in frictional contact with said blade-holder.

9. In a razor-stropping device, the combination of a frame provided with a handle for imparting bodily movement thereto, a 95 plurality of spindles secured to said frame, means for removably securing said spindles to said frame, a blade-holder revolvably mounted on one of said spindles, and a roller mounted upon another of said spindles and 100 in frictional contact with said blade-holder.

10. In a razor-stropping device, the combination of a base-plate, two parallel spindles removably secured to said base-plate, means for rigidly securing said spindles to 105 said base plate, a blade-holder revolvably mounted on one of said spindles, a friction-member mounted on the other spindle in frictional contact with said blade-holder, and a plurality of standards rigidly secured 110 to said base-plate for supporting the strop.

11. In a razor-stropping device, the combination of a frame, a handle removably secured thereto, two parallel spindles removably secured to said frame, a blade-holder 115 revolvably mounted upon one of said spindles, and a friction-member revolvably mounted upon the other spindle and in frictional contact with said blade-holder.

12. In a razor-stropping device, the combination of a base-plate formed from sheet metal bent over upon itself to form a clamping-member, a handle secured thereto, a plurality of standards to support the strop secured to said base-plate, and means for holding and oscillating a razor blade secured to 120 said base-plate.

13. In a razor-stropping device, the combination of a base plate formed of sheet metal bent over upon itself to form a clamp- 130

ing-member, a handle removably secured to said clamping-member, a pair of parallel spindles removably secured to said clamping-member, a blade-holder revolvably mounted 5 on one of said spindles, a friction-roller in frictional contact with said blade-holder revolvably mounted on the other spindle, and standards secured to said base plate to support the strop and to increase the surface of 10 contact between the roller and the strop.

14. In a razor-stropping device, the combination of a base plate, a handle, means for removably securing said handle to said base plate, a plurality of standards to support the 15 strop rigidly secured to said base plate, and means secured to said base plate for holding

and actuating a razor blade to and from the strop.

15. In a razor-stropping device, the combination of a base plate, a handle secured thereto, a roller for engaging the strop, a bladeholder in frictional contact with the peripheral surface of said roller, and a pair of standards to support the strop secured to said base plate and arranged one on either 20 25 side of said roller.

In testimony whereof, I sign this specification in the presence of two witnesses.

ELMER I. YOUNG.
